[57] CLAIM

The ornamental design for a toy mask, as shown and described.

DESCRIPTION

FIG. 1 is a front elevational view of a toy mask showing
my new design;

FIG. 2 is a rear elevational view thereof;

FIG. 3 is a top plan view thereof;

FIG. 4 is a bottom plan view thereof; and

FIG. 5 is a right side elevational view thereof, the side opposite being substantially a mirror image.
